UNITED STATES PATENT OFFICE.

JAMES W. RANDOLPH, OF HANDLEY, TEXAS.

PLOW.

1,123,922.

Specification of Letters Patent.

Patented Jan. 5, 1915.

Application filed July 26, 1913. Serial No. 781,318.

To all whom it may concern:

Be it known that I, JAMES W. RANDOLPH, a citizen of the United States, residing at Handley, in the county of Tarrant and State of Texas, have invented a new and useful Plow; and I do hereby declare the following to be a full, clear, and exact description of the invention, such as will enable others skilled in the art to which it applies to make and use the same.

This invention relates to the art of plows and the like, and particularly to a new and useful attachment for such implements, which attachment may be termed "heel sweeps."

An object of the invention is to provide "heel sweeps" for a plow, and of such a construction that the sweeping wings may be adjusted at different angles, or both the wings as one body may be adjusted relative to the plow beam standard so that the furrow on one side of the plow may be swept more than the furrow on the opposite side, and vice versa.

The invention comprises further features and combination of parts, as hereinafter set forth, shown in the drawings and claimed.

In the drawings:—Figure 1 is a view in perspective of a plow, showing the same equipped with the improved furrow "heel wings." Fig. 2 is a plan view of the plow showing the handles thereof removed, with the wings adjusted in one position. Fig. 3 is a view similar to Fig. 2 showing the wings adjusted singly in other positions. Fig. 4 is a view similar to Figs. 2 and 3 showing the wings adjusted in other positions. Fig. 5 is a detail view of the wings detached from a standard, showing how the wings may be adjusted independently. Fig. 6 is a detail vertical sectional view through the structure shown in Fig. 2, showing one side of the heel plate in elevation. Fig. 7 is a bottom plan view of the wings.

Referring more particularly to the drawings, 1 designates the plow beam, having the usual handle 2, and provided with a standard 3, to which the usual plow point is fixed at 4, the plow point being denoted by the numeral 5.

Connected at 6 to the under curved portion of the standard 3 is an angularly constructed member constituting a heel plate denoted by the numeral 7. This plate is constructed upon its under face with heels

or enlargements 8, which are provided with substantially cutting curved edges 9, so as to pass easily through the soil. This plate 7 has a comparatively thin portion connecting said enlargements 8, which thin portion is provided with an aperture 10, through which screws 11 pass, and into the under face of the standard 3. The under face of the standard 3 is constructed with a plurality of holes 12, to receive the screws 11, so that the plate 7 may be held in adjusted positions. The heel plate 7 not only forms a steady base for the standard 3, but the enlargements 8 thereof act as means for adjustably carrying the wings 16, while the cutting edges 9, act to more thoroughly trim the furrow in the rear of the plow point 5, as well as cutting up the clods, and also making shallow channels adjacent each side of the furrow owing to the enlargement. Owing to the comparatively thin portion between the enlargements said enlargements are allowed to yield slightly as the heel plate passes through the furrow. Said enlargements 8 constitute heel members angular in cross section, the outer faces of which and the outer face of the comparatively thin portion between said enlargements or heel members inclined downwardly and laterally, so as to insure that the heel plate will travel under the earth that is turned by the plow point. The ends of the plate 7 are provided with two sets of holes 13 and 14, to receive the screws 15, which hold the wings 16 (which wings are in the form of blades) in adjusted positions. By removing the screws 15, and readjusting the same in the holes 13 and 14, the blades or heel wings may be adjusted in different positions to those shown in Fig. 1, as shown in Figs. 2 and 3.

The invention having been set forth, what is claimed as new and useful is:—

1. In combination with a plow standard including a plow share, a substantially U-shaped plate, the central portion of which being constructed comparatively thin, means passing through the central portion for adjustably securing the plate at an angle to the lower end of the standard, the sides of the substantially U-shaped plate having heel members angular in cross section and provided with forward curved cutting edges, wings, the outer faces of the heel members being inclined laterally and downwardly, and means for adjustably se-

curing the wings to the laterally and downwardly inclined faces of said heel members.

2. A substantially U-shaped heel plate for a plow standard, the central portion of which being constructed comparatively thin, the opposite side portions of the heel plate being enlarged and constituting heel members angular in cross section, said heel members having forward curved cutting edges, 10 the outer faces of the heel members and the

outer face of the comparatively thin central portion being inclined laterally and downwardly.

In testimony whereof I have signed my 15 name to this specification in the presence of two subscribing witnesses.

JAMES W. RANDOLPH.
